Primary Examiner — Kevin Rudzinski(74) *Attorney, Agent, or Firm* — DLA Piper LLP (US)(57) **CLAIM**

The ornamental design for a lighting device, as shown and described.

DESCRIPTION

FIG. 1 is a perspective view of a lighting device taken from the front, right side and top thereof, showing our new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof; and,
FIG. 7 is a bottom plan view thereof.

The broken lines illustrating portions of the lighting device are included to show environmental structures and form no part of the claimed design.
